John H. Reed

John H. Reed

UNITED STATES PATENT OFFICE.

JOHN W. BURT, OF NEW YORK, N. Y.

DESIGN FOR AN ANKLET.

Specification forming part of Design No. 1,572, dated May 6, 1862.

To all whom it may concern:

Be it known that I, JOHN W. BURT, of the city, county, and State of New York, have produced a new and ornamental Design for an Anklet; and I do hereby declare that the following is a full, clear, and exact description of the same, reference being had to the accompanying drawings, forming a part of this specification, in which—

Figure 1 represents a plan of my anklet when the same is spread out and placed flat down on a table. Fig. 2 is a side elevation of the same when attached to the leg.

Similar letters of reference in both views indicate corresponding parts.

My anklet, which is particularly intended for little boys, is applied similarly to the leggins commonly worn by "zouaves" and others. Such leggins are cut out with plain circular edges, and when applied to the leg they have the form of frustums or truncated cones, giving to the leg a clumsy and coarse appearance.

My anklet is cut out with graceful sweeps and arcs in such a manner that its edges when applied to the leg form a double ogee, one on either side of the leg. Furthermore, I have connected the several pieces which constitute my anklet, so as to produce a peak and to make the same fit to the instep of the foot, giving to the whole a neat and graceful appearance.

By referring to the drawings it will be noticed that the upper edge *a* of the anklet *A* is cut out with a descending or concave sweep *b*, which joins the convex arc *c*. This arc *c* meets a similar arc *d*, which extends down to

the end of the edge. When joined together or when applied to the leg, the upper edge of the anklet forms two ogees *e*, commencing in front of the leg and extending in opposite directions over the sides of the leg until they meet in the rear. The lower edge *f* is cut out with various sweeps and arcs, which appear irregular when the anklet is spread, as shown in Fig. 1, on account of the peak *g*, produced by the peculiar manner of connecting the several pieces which constitute the anklet; but when the anklet is applied to the leg, said lower edge *f* forms also two ogees *h*, as clearly shown in Fig. 2, and the peak *g* gives to the front side of the anklet a graceful sweep and causes it to conform to the shape of the instep.

The anklet may be fastened to the leg with buckles *i*, attached to elastic bands *j*, whereby said buckles extend or contract, so as to conform to different-sized legs, or it may be fastened by means of buttons or by any other desirable means. When properly attached, however, my anklet has a graceful and neat appearance, and will be worn as an ornament rather than as a protection of the leg.

Having thus fully described my design, what I claim as new, and desire to secure by Letters Patent, is—

The two ogees *e* on the upper edge of an anklet *A*, and the two ogees *h* on its lower edge, and also the peak *g*, formed in the manner shown and described.

JOHN W. BURT.
